UNITED STATES PATENT OFFICE

WALTER S. RUNNELS, OF KALAMAZOO, MICHIGAN

VENDING MACHINE

Application filed February 28, 1929. Serial No. 343,491.

The main objects of this invention are:

First, to provide in a vending machine a coin controlled delivery mechanism which is not likely to become clogged or inoperative in use or injure the merchandise as it is delivered.

Second, to provide a vending machine delivery mechanism in which the ejecting member delivers an article when reciprocated in either direction.

Third, to provide in a vending machine an improved coin released locking mechanism.

Fourth, to provide in a vending machine a coin released locking mechanism arranged to prevent manipulation resulting in the discharge of more than one piece of merchandise on the introduction of a single coin.

Objects pertaining to details and economies of my invention will definitely appear from the description to follow. The invention is defined in the claims.

A structure which embodies the features of my invention is clearly illustrated in the accompanying drawing, in which:

25 Fig. 1 is a front elevation of a vending machine embodying my improvements.

Fig. 2 is a view mainly in vertical central section on line 2—2 of Figs. 1, 3, 4 and 5.

30 Fig. 3 is a fragmentary inside view of the coin delivery mechanism and certain attached parts removed from the main body of the machine.

Fig. 4 is a fragmentary elevation of the mechanism with the parts shown in Fig. 3 removed.

35 Fig. 5 is a horizontal section on a line corresponding to line 5—5 of Figs. 1, 2 and 6 showing details of the merchandise delivery mechanism.

40 Fig. 6 is a detail vertical section on line 6—6 of Fig. 5.

Fig. 7 is an enlarged detail section on line 7—7 of Figs. 11 and 12 showing the relation of the coin when in releasing position to the parts released.

Fig. 8 is a fragmentary section corresponding to that of Fig. 7 with the parts in another position.

50 Fig. 9 is a fragmentary view partially in section on a line corresponding to line 9—9

of Fig. 6 showing details of the coin controlled locking dog and the actuating slide controlled thereby.

Fig. 10 is a fragmentary view corresponding to that of Fig. 9 showing the parts in another position.

Fig. 11 is an enlarged detail view partially in section on line 11—11 of Fig. 2.

Fig. 12 is a plan view of parts of the ejector mechanism, the ejector being omitted.

Fig. 13 is a perspective view of the ejector.

Fig. 14 is an enlarged detail partially in section on line 14—14 of Fig. 3.

In the embodiment illustrated I provide a casing 1 having a removable front wall 2 and provided with vertical magazines 3 in which the merchandise to be vended is stacked one piece upon another. The front wall 2 is provided with a coin receiving opening 4 and carries suitable mechanism for detecting and rejecting improper coins. This mechanism is preferably that which is made the subject matter of my co-pending application and, as the details thereof form no part of this invention they are not further described herein. It is deemed sufficient to state that this coin detecting mechanism is adapted to deliver the coin to the coin controlled ejector or delivery mechanism, the subject matter of this application.

70 The removable front wall is provided with a lug 5 at its upper end engageable with a coacting lug 6 within the cabinet and has a mechanism housing member 7 attached to its lower end and supporting a lug 8 coacting with a suitable keeper 9 in the casing. The housing member 7 has merchandise chutes or pockets 10 at each side into which the merchandise is ejected and from which it may be removed. These cabinet parts are arranged to provide a housing or chamber 11 for the delivery mechanism.

75 The delivery slide or ejector 12 is provided with a pair of pockets 13 adapted to be alternately brought below the magazines 3 as the ejector is reciprocated, these pockets being of such size as to permit a piece of merchandise to drop into the same.

80 The ejector is provided with merchandise supporting members 14 adapted to pass under 100

the magazine as the pocket moves from below it with a piece of merchandise to discharging position. This ejector is reciprocatingly supported on a table 15 provided with A-shaped tracks 16 coacting with grooves 17 in the ejector slide so that the ejector moves quite freely.

The table 15 is provided with a downwardly projecting bracket 18 at its rear edge secured to the rear wall of the cabinet. Below this table and in spaced relation thereto is a plate-like supporting bracket 19.

Between the table and the supporting bracket 19 I mount a slide 20 which is slidably supported on the way member 15 by means of the headed studs 21 engaging the slot 22 in the member 15. The actuating slide is further guided in its movement by means of a V-shaped downwardly facing way 210 on the under side of the member coacting with a groove-like guide 211 in the slide.

This actuating slide 20 is provided with a rack 23 meshing with a pinion 24 on the hand lever 25 disposed on the outside of the casting so that as the hand lever is oscillated between the stops 26 the actuating slide is actuated. The actuating slide is provided with a stud 27 extending through a slot 28 in the member 15 and projecting through a hole 28 in the ejector. A washer 29 and screw 30 tapped into the stud retain the ejector in assembled position.

The slide is controlled by the coin released locking dog 31 which is pivoted at 32 on the bracket 19 so that it is supported at the under side of the slide. This locking dog is yieldingly held in a central position by means of the spring pressed pin 33 engaging a V notch 34 in the tail of the dog. Stops 35 coacting with the tail limit the swing of this dog.

The dog is provided with a coin slot 36 positioned below the coin slot 37 in the way member to which the coins, as 38, are delivered by the coin control mechanism. Below this coin slot in the locking dog is a coin pocket 40 of such length that the coin may drop from the pocket when the dog is swung to its extreme position in either direction. When the coin is in the pocket it not only engages the slot or recess in the dog but projects above the same into engagement with the flange-like members 41 on the actuating slide, see Figs. 7 and 8, so that the initial movement of the actuating slide imparted through the lever 26 will swing the dog on its pivot. The actuating slide is provided with a pair of spaced stop members 42, see Fig. 9, arranged to coact with one of the stop members 43 on the locking dog.

When the locking dog is in its central position one of the stops 43 lies between the ends of the stops 42, thereby permitting a limited movement of the actuating slide sufficient to swing the dog in the event a coin is present in the coin pocket 40, thereby swinging the dog

out of stopping position and allowing further actuation of the slide.

To prevent repeated partial strokes such as might be sufficient to discharge merchandise or to result in the clogging of the machine, the stops 42 are provided with ratchet teeth 44. These teeth are arranged so that when the locking dog is tilted to releasing position one of the stops 43 coacts with the ratchet teeth of one of the stops 42, the other stop 43 being in front of the other stop 42 so that the slide cannot be returned to its initial position in a reverse direction until its stroke is fully completed. At this time the locking dog is released so that it swings to locking position and it is necessary to introduce another coin to release it. As stated, a piece of merchandise is delivered on each full stroke in either direction.

With this arrangement when the ejector is at one end of its stroke one pocket is in position to receive a package of merchandise, the other being in discharging position over its discharge pocket 10. The mechanism is positively locked, the parts are strong and not easily broken and at the same time are quite simple in structure.

To prevent the introduction of a coin into the delivery mechanism when merchandise is exhausted, I provide a coin stop 45 which is pivoted at 46 to project through a slot 47 in the wall of the coin chute to deflect a coin introduced from the passage leading to the coin slot 37 above the coin pocket 40. This stop is held normally in retracted position as shown by dotted lines in Fig. 2 by the merchandise depressing the cross piece 48 on the lower end of the rod 49 connected to the stop 45. These parts are arranged in the partition 50 between the magazines.

To prevent the engagement of the ejector 12 with a tool manipulated through the discharge pockets 10, the pocket walls 51 are positioned so that the outer wall of the pockets lies within the partition when the pocket is in receiving position—see Fig. 6—, brackets being provided with flanges 52 at their outer ends which enter recesses 53 provided therefor in the outer walls of the chutes when the pockets are in their discharging position—see the left-hand side of Fig. 6. This prevents a tool such as a bench bar or screw driver being engaged with the end of the ejector in either position to exert pressure thereon which might break the locking dog and thereby prevent free manipulation of the ejector.

I have illustrated and described my improvements in an embodiment which has been found in practice to be highly satisfactory. I have not attempted to illustrate or describe certain modifications or adaptations as I believe the disclosure made will enable those skilled in the art to embody or adapt my improvements as may be desired.

Having thus described my invention what I claim as new and desire to secure by Letters Patent is:

1. In a coin controlled vending machine, the combination with magazines disposed side by side, of a table mounted centrally below said magazines and provided with a pair of spaced ejector ways on its upper side and a longitudinal slot between said ejector ways, said table also having a downwardly facing actuating slide way and a longitudinal way slot adjacent said actuating slide way, said table being provided with a central coin slot, an ejector slidably mounted on said ejector ways and adapted to be alternately brought into receiving position relative to said magazines, an actuating slide coacting with said actuating slide way on said table and provided with headed studs reciprocating in said way slot therein, said actuating slide being provided with a stud reciprocating in said slot between said ejector ways and secured centrally to said ejector, said actuating slide having spaced alined elongated stop members provided with ratchet teeth, said slide being provided with coin receiving slots alternately alined with said coin slot of said table, a supporting bracket below said way member, a coin controlled locking dog pivotally mounted on said bracket and provided with a coin recess disposed in front of its pivot and below said coin slot of said table and with detents disposed on opposite sides of its pivot to coact with said stops, one of said detents lying between and coacting with adjacent ends of said stops when in initial position thereby permitting limited movement of the actuating slide, said detents alternately coacting with the ratchet teeth of said stops preventing return movement of the slide until a full stroke has been completed, and a spring acting to yieldingly hold said dog to initial locking position. 70
2. In a coin controlled vending machine, the combination with magazines disposed side by side, of a table mounted centrally below said magazines and provided with a pair of spaced ejector ways on its upper side and a longitudinal slot between said ejector ways, said table also having a downwardly facing actuating slide way and a longitudinal way slot adjacent said actuating slide way, said table being provided with a central coin slot, an ejector slidably mounted on said ejector ways and adapted to be alternately brought into receiving position relative to said magazines, an actuating slide coacting with said actuating slide way on said table and provided with headed studs reciprocating in said way slot therein, said actuating slide being provided with a stud reciprocating in said slot between said ejector ways and secured centrally to said ejector, said actuating slide having spaced stops and being provided with coin receiving slots alternately alined with said coin slot of said table, a supporting bracket below said table, a coin controlled locking dog pivotally mounted on said bracket and provided with a coin recess disposed in front of its pivot and below said coin slot of said table and with detents disposed on opposite sides of its pivot to coact with said stops, one of said detents lying between and coacting with adjacent ends of said stops when in initial position thereby permitting limited movement of the actuating slide, said detents alternately coacting with the ratchet teeth of said stops preventing return movement of the slide until a full stroke has been completed, a spring acting to yieldingly hold said dog to initial locking position, and a coin support open at its ends disposed below said coin recess of said dog. 95
3. In a coin controlled vending machine, the combination with magazines disposed side by side, of a table mounted centrally below said magazines and provided with a pair of spaced ejector ways on its upper side and a longitudinal slot between said ejector ways, said table also having a downwardly facing actuating slide way and a longitudinal way slot adjacent said actuating slide way, said table being provided with a central coin slot, an ejector slidably mounted on said ejector ways and adapted to be alternately brought into receiving position relative to said magazines, an actuating slide coacting with said actuating slide way on said table and provided with headed studs reciprocating in said way slot therein, said actuating slide being provided with a stud reciprocating in said slot between said ejector ways and secured centrally to said ejector, said actuating slide having spaced stops and being provided with coin receiving slots alternately alined with said coin slot of said table, a supporting bracket below said table, a coin controlled locking dog pivotally mounted on said bracket and provided with a coin recess disposed in front of its pivot and below said coin slot of said table and with detents disposed on opposite sides of its pivot to coact with said stops, one of said detents lying between and coacting with adjacent ends of said stops when in initial position thereby permitting limited movement of the actuating slide, said detents alternately coacting with the ratchet teeth of said stops preventing return movement of the slide until a full stroke has been completed, a spring acting to yieldingly hold said dog to initial locking position, and a coin support open at its ends disposed below said coin recess of said dog. 100
4. In a coin controlled vending machine, the combination with magazines disposed side by side, of a table mounted centrally below said magazines and provided with a pair of spaced ejector ways on its upper side and a longitudinal slot between said ejector ways, said table also having a downwardly facing actuating slide way and a longitudinal way slot adjacent said actuating slide way, an ejector slidably mounted on said ejector ways and adapted to be alternately brought into receiving position relative to said magazines, an actuating slide coacting with said actuating slide way on said table and provided with headed studs reciprocating in said way slot therein, said actuating slide being provided with a stud reciprocating in said slot between said ejector ways and secured centrally to said ejector, said actuating slide having spaced alined elongated stop members 110
5. In a coin controlled vending machine, the combination with magazines disposed side by side, of a table mounted centrally below said magazines and provided with a pair of spaced ejector ways on its upper side and a longitudinal slot between said ejector ways, said table also having a downwardly facing actuating slide way and a longitudinal way slot adjacent said actuating slide way, an ejector slidably mounted on said ejector ways and adapted to be alternately brought into receiving position relative to said magazines, an actuating slide coacting with said actuating slide way on said table and provided with headed studs reciprocating in said way slot therein, said actuating slide being provided with a stud reciprocating in said slot between said ejector ways and secured centrally to said ejector, said actuating slide having spaced alined elongated stop members 120
6. In a coin controlled vending machine, the combination with magazines disposed side by side, of a table mounted centrally below said magazines and provided with a pair of spaced ejector ways on its upper side and a longitudinal slot between said ejector ways, said table also having a downwardly facing actuating slide way and a longitudinal way slot adjacent said actuating slide way, an ejector slidably mounted on said ejector ways and adapted to be alternately brought into receiving position relative to said magazines, an actuating slide coacting with said actuating slide way on said table and provided with headed studs reciprocating in said way slot therein, said actuating slide being provided with a stud reciprocating in said slot between said ejector ways and secured centrally to said ejector, said actuating slide having spaced alined elongated stop members 125

vided with a stud reciprocating in said slot between said ejector ways and secured centrally to said ejector, said actuating slide having spaced stops, a supporting bracket below said table, and a coin controlled locking dog pivotally mounted on said bracket and provided with detents disposed on opposite sides of its pivot to coact with said stops, one of said detents lying between and coacting with adjacent ends of said stops when in initial position thereby permitting limited movement of the actuating slide.

5. In a coin controlled vending machine, the combination with magazines disposed side by side, of a table provided with a coin slot, an ejector slidably mounted on said table and adapted to be alternately brought into receiving position relative to said magazines, an actuating slide slidably mounted on the 10 under side of said table and operatively connected to said ejector, said actuating slide being provided with a rack and with spaced alined elongated stop members provided with ratchet teeth, said slide being provided with coin receiving slots alternately alined 15 with said coin slot of said table, a supporting bracket below said table, a coin controlled locking dog pivotally mounted on said bracket and provided with a coin recess disposed in front of its pivot and below said coin slot of said way member 20 and with detents disposed on opposite sides of its pivot to coact with said stops, one of said detents lying between and coacting with adjacent ends of said stops when in initial 25 position, thereby permitting limited movement of the actuating slide, a spring acting to yieldingly hold said dog to initial locking position, a coin support open at its ends disposed below said coin recess of said dog, and a pinion coacting with said rack and provided with a handpiece.

40. In a coin controlled vending machine, the combination with magazines disposed side by side, of a table provided with a coin slot, an ejector slidably mounted on said table and adapted to be alternately brought into receiving position relative to said magazines, an actuating slide slidably mounted on the under side of said table and operatively connected to said ejector, said actuating 45 slide being provided with a rack and with spaced alined elongated stop members provided with ratchet teeth, a supporting bracket below said table, a coin controlled locking dog pivotally mounted on said bracket and provided with detents disposed on opposite sides of its pivot to coact with said stops, one of said detents lying between and coacting with adjacent ends of said stops when in initial position, thereby permitting limited movement of the actuating slide, a spring 50 acting to yieldingly hold said dog to initial locking position, and a pinion coacting with said rack and provided with a handpiece.

60. In a coin controlled vending machine, the combination with magazines disposed side by side, of a table provided with a coin slot, an ejector slidably mounted on said table and adapted to be alternately brought into receiving position relative to said magazines, an actuating slide slidably mounted on the under side of said table and operatively connected to said ejector, said actuating 65 slide being provided with a rack and with spaced alined elongated stop members provided with ratchet teeth, a supporting bracket below said table, a coin controlled locking dog pivotally mounted on said bracket and provided with detents disposed on opposite sides of its pivot to coact with said stops, one of said detents lying between and coacting with adjacent ends of said stops when in initial position, thereby permitting limited movement of the actuating slide, a spring 70 acting to yieldingly hold said dog to initial locking position, and a pinion coacting with said rack and provided with a handpiece.

75. In a coin controlled vending machine, the combination with magazines disposed side by side, of a table provided with a coin slot, an ejector slidably mounted on said table and adapted to be alternately brought into receiving position relative to said magazines, an actuating slide slidably mounted on the under side of said table and operatively connected to said ejector, said actuating slide being provided with a rack and with spaced alined stop members, said slide being provided with coin receiving slots alternately alined with said coin slot of said table, a supporting bracket below said table, a coin controlled locking dog pivotally mounted on said bracket and provided with a coin recess disposed in front of its pivot and below said coin slot of said way member 80 and with detents disposed on opposite sides of its pivot to coact with said stops, one of said detents lying between and coacting with adjacent ends of said stops when in initial position, thereby permitting limited movement of the actuating slide, a spring acting to yieldingly hold said dog to initial locking position, a coin support open at its ends disposed below said coin recess of said dog, and a pinion coacting with said rack and provided with a handpiece.

85. In a coin controlled vending machine, the combination with magazines disposed side by side, of a table provided with a coin slot, an ejector slidably mounted on said table and adapted to be alternately brought into receiving position relative to said magazines, an actuating slide slidably mounted on the under side of said table and operatively connected to said ejector, said actuating slide being provided with a rack and with spaced alined elongated stop members provided with ratchet teeth, said slide being provided with coin receiving slots alternately alined with said coin slot of said table, a supporting bracket below said table, a coin controlled locking dog pivotally mounted on said bracket and provided with a coin recess disposed in front of its pivot and below said coin slot of said way member 90 and with detents disposed on opposite sides of its pivot to coact with said stops, one of said detents lying between and coacting with adjacent ends of said stops when in initial position, thereby permitting limited movement of the actuating slide, a spring acting to yieldingly hold said dog to initial locking position, a coin support open at its ends disposed below said coin recess of said dog, and a pinion coacting with said rack and provided with a handpiece.

95. In a coin controlled vending machine, the combination with magazines disposed side by side, of a table provided with a coin slot, an ejector slidably mounted on said table and adapted to be alternately brought into receiving position relative to said magazines, an actuating slide slidably mounted on the under side of said table and operatively connected to said ejector, said actuating slide being provided with a rack and with spaced alined elongated stop members provided with ratchet teeth, a supporting bracket below said table, a coin controlled locking dog pivotally mounted on said bracket and provided with detents disposed on opposite sides of its pivot to coact with said stops, one of said detents lying between and coacting with adjacent ends of said stops when in initial position, thereby permitting limited movement of the actuating slide, a spring acting to yieldingly hold said dog to initial locking position, and a pinion coacting with said rack and provided with a handpiece.

100. In a coin controlled vending machine, the combination with a plurality of magazines, of an ejector slidably mounted below said magazines and adapted to be alternately brought into receiving position relative to said magazines, an actuating slide connected to said ejector to reciprocate therewith and 105

110

115

120

125

130

- provided with spaced coin slots adapted to be successively brought into coin receiving position, said slide being also provided with spaced stop members provided with ratchet teeth, a pivotally mounted coin controlled locking dog for said actuating slide provided with a coin recess with which said coin slots of said slide are adapted to alternately register and with detents coacting with said stops, 5 one of the detents lying between the stops when in initial position permitting limited movement of the actuating slide to release the dog through a coin moved by said slide, said detents alternately coacting with the ratchet teeth of said stops preventing return movement of the slide until completion of its stroke in one direction, in which position the slide is again locked by said dog, and a coin support open at its ends disposed below said coin recess of said dog. 10
10. In a coin controlled vending machine, the combination with a plurality of magazines, of an ejector slidably mounted below said magazines and adapted to be alternately brought into receiving position relative to said magazines, an actuating slide connected to said ejector to reciprocate therewith, said slide being also provided with spaced stop members provided with ratchet teeth, and 15 a pivotally mounted coin controlled locking dog for said actuating slide provided with detents coacting with said stops, one of the detents lying between the stops when in initial position permitting limited movement of the slide to release the dog through a coin moved by said slide, said detents alternately coacting with the ratchet teeth of said stops preventing return movement of the slide until completion of its stroke in one direction, in which position the slide is again locked by said dog. 20
11. In a coin controlled vending machine, the combination with a plurality of magazines, of an ejector slidably mounted below said magazines and adapted to be alternately brought into receiving position relative to said magazines, an actuating slide connected to said ejector to reciprocate therewith and provided with spaced coin slots adapted to be successively brought into coin receiving position, said slide being also provided with spaced stop members, a pivotally mounted coin controlled locking dog for said actuating slide provided with a coin recess with 25 which said coin slots of said slide are adapted to alternately register and with detents coacting with said stops, one of the detents lying between the stops when in initial position permitting limited movement of the actuating slide to release the dog through a coin moved by said slide, and a coin support open at its ends disposed below said coin recess of said dog. 30
12. In a coin controlled vending machine, 35 the combination with a plurality of magazines, of an ejector slidably mounted below said magazines and adapted to be alternately brought into receiving position relative to said magazines, an actuating slide connected to said ejector to reciprocate therewith, said slide being also provided with spaced stop members, and a pivotally mounted coin controlled locking dog for said actuating slide provided with detents coacting with said stops, one of the detents lying between the stops when in initial position permitting limited movement of the actuating slide to release the dog through a coin moved by said slide. 40
13. In a coin controlled vending machine, the combination with a plurality of magazines, of a slidably mounted ejector adapted to be alternately brought into receiving position relative to said magazines, means for actuating said ejector, and a pivotally mounted coin controlled locking dog operatively associated with said ejector and provided with a pair of spaced detents, and a pair of coacting stops operatively connected with said ejector and provided with ratchet teeth with which said detents on said locking dog coact to prevent return movement of the ejector prior to the completion of its full stroke in one direction. 45
14. In a coin controlled vending machine, the combination with a plurality of magazines, of a slidably mounted ejector adapted to be alternately brought into receiving position relative to said magazines, means for actuating said ejector, a coin controlled locking dog operatively associated with said ejector and provided with a pair of spaced detents, and a pair of coacting stops operatively connected with said ejector, said ejector also having ratchet teeth operatively connected thereto and with which said detents on said locking dog coact to prevent return movement of the parts until completion of the stroke of the ejector in one direction. 50
- In witness whereof I have hereunto set my hand. 55
